UNITED STATES PATENT OFFICE.

FREDERICK M. FURBER, DECEASED, LATE OF REVERE, MASSACHUSETTS; BY SAMUEL R. CUTLER, ADMINISTRATOR, OF REVERE, MASSACHUSETTS, ASSIGNOR TO UNITED SHOE MACHINERY CORPORATION, OF PATERSON, NEW JERSEY, A CORPORATION OF NEW JERSEY.

SKIVING MACHINE.

Application filed April 16, 1926. Serial No. 102,491.

This invention relates to skiving machines and is herein illustrated as embodied in a machine particularly designed to skive filling pieces for boots and shoes.

5 In British Patent No. 206,176, there is disclosed a filling piece, hereinafter referred to as a "filler", made of sheet material and shaped to fill the cavity in the forepart and shank portion of the bottom of a welt shoe 10 which is included within the inseam. This filler has an outline to correspond to that of the inseam and a recess in its forepart to correspond to the curvature, both transverse and longitudinal, of the bottom of the insole of the shoe, the illustrated machine 15 herein disclosed being designed particularly to skive such a recess in a filler of the type of that shown in the patent.

The material of which these fillers are 20 made is commonly paper felt which has been impregnated with an asphaltic substance and highly compressed, such material by reason of its stiffness, its felted character and the presence of the thermoplastic im- 25 pregnant presenting certain difficulties in the skiving operation.

It is an object of this invention to provide an improved skiving machine adapted for recessing fillers of the type referred to 30 above.

According to one feature of the present invention, there is provided a plate having a suitable matrix into which a blank is pressed so as to distort it, a knife driven in a manner to produce a draw cut and means for causing the blank to be traversed by the knife. The matrix plate provides a firm support against which the blank may be pressed and thus distorted properly; and 40 the draw cut executed by the knife facilitates the skiving operation. In the illustrated machine the knife is moved very rapidly in an orbital path in the plane of its cut, and the matrix plate is reciprocated in a path to feed a blank carried by it to the knife, the blank being pressed into the matrix by a roll which engages the moving blank just in front of the edge of the knife.

In the course of the skiving operation, in 50 which a certain amount of heat is generated, the impregnant substance of the blank commonly becomes somewhat plastic and sticky and tends to cause the cut produced by the knife to be somewhat ragged. According

to another feature of the invention, means 55 are provided for heating the knife. The hot knife apparently melts the impregnant substance which it encounters approximately to the consistency of a liquid so that the knife passes easily through it. In the illustrated construction the heating means is an electric heat unit held closely above the moving knife.

According to another feature of the invention a magazine is provided for a stack of 60 blanks from which the blanks are received one by one by the matrix plate and delivered by the matrix plate to the knife, the plate being reciprocated from receiving to delivering position.

After the blanks have been skived, it is 65 desirable to remove them from the machine. According to another feature of the invention, the matrix plate carries each blank entirely past the skiving mechanism in which 70 position it is removed from the plate. In the illustrated machine a picker is actuated to lift each skived blank from the plate when the plate carries the blank beneath it, the blank being held raised until the matrix 75 plate, in its return to blank receiving position, operates mechanism which strips the skived blank from the picker and permits it to fall into a suitable receptacle.

These and other features of the invention 80 including certain details of construction and combinations of parts will be described as embodied in an illustrative machine and pointed out in the appended claims.

Referring now to the accompanying drawings,

Figure 1 is a side elevation of a machine in which the present invention is embodied;

Figure 2 is a plan view of the machine;

Figure 3 is a rear elevation of the machine;

Figure 4 is a perspective showing more particularly the mounting of the feed slide and the matrix plate;

Figure 5 is a detail principally in section 100 showing more particularly the connection between the feed slide and the matrix plate;

Figure 6 is a plan of a filler after it has 105 been operated upon;

Figure 7 is a section taken on the line 7-7 of Fig. 6, and

Figure 8 is a detail principally in section 110 showing the mounting of the knife.

Although the invention is not limited to operating upon any particular kind of work, the illustrated machine, as has been stated, is designed particularly to skive a filler made 5 of sheet material such as is indicated at 100 in Fig. 6 in such manner as to produce a recess like that indicated at 200, such filler being made, for example, of felt impregnated with a thermoplastic substance which 10 is normally hard and stiff but becomes soft when heated sufficiently. In the operation of the machine, the fillers are stacked in a magazine and fed one by one from the bottom of the stack upon a matrix plate which 15 then moves past a skiving mechanism including a presser roll and a knife, the matrix being so shaped that, as the matrix plate, with the filler upon it, passes beneath the presser roll to the knife, a selected portion 20 of the forepart of the filler is held up by the matrix plate in the path of the knife and cut off to produce the recess 200.

Referring first more particularly to Figures 4 and 5, a main plate 9 has fastened to 25 it three auxiliary plates 15, 17 and 18. The auxiliary plate 15 has a U-shaped recess shaped to fit about the toe portion of a filler. The auxiliary plate 17 has a middle portion shaped to raise the desired portion of the 30 filler into the path of cut of the knife. The auxiliary plate 18 is a thin one the surface of which is at the same level as the extreme forward end of the auxiliary plate 17. The plate 9 is thicker at its rear portion than at 35 its front portion, the two portions being separated by a shoulder 20 which engages the rear end of a filler when the filler is in the matrix, the top surface of the rear portion of the main plate 9 being substantially 40 at the same level as the top surface of the auxiliary plate 15. It will be noted that the auxiliary plate 15 has two narrow extensions 22 located one at each side of the auxiliary plate 17, the purpose of which is to prevent 45 the knife from digging into the filler farther than is desired during the skiving operation. The whole structure, made up of the plates 9, 15, 17, and 18, will be referred to herein-after as the matrix plate since obviously it 50 might be made of a single piece of metal. It is made in parts merely to facilitate changing the shape of the matrix, it being noted that the auxiliary plates 15, 17 and 18 are fastened to the main plate 9 by screws so as 55 to be readily removable and replaceable by plates of different shapes.

This matrix plate is slidable horizontally in guides 19, which are rigid with the frame of the machine, and has on its under side a 60 rack 21 (Fig. 2) by means of which it is reciprocated. The rack is engaged by a pinion 23 (Fig. 3) fast to a shaft 25 (Figs. 2 and 3) which has also fast at one end thereof a small gear 27 with which meshes a segmental rack 29. This segmental rack (Fig.

1) is pivoted to the frame of the machine at 31 and is rocked to and fro by a link 33 pivoted at one end to the segmental rack and at the other to a crank arm 35 fast to a shaft 37, said shaft being driven, through a 70 one-revolution clutch, by a belt 39 and pulley 40. With this construction the matrix plate is caused to make one complete reciprocation whenever one revolution is imparted to the shaft 37. In Figure 2 a stack of fillers 100 75 is shown in the magazine. Just as the matrix plate reaches its rearward position (the one shown in this figure) the lowermost filler is pushed part way out of the magazine into the position indicated in 80 dotted lines in which position it rests in the matrix which has been described above and is best shown in Figure 4. As the matrix plate moves forward (to the left as viewed in Figure 1) the filler is carried beneath a 85 presser roll 41 and skived by a knife 43 to produce the result shown in Figures 6 and 7. In order to support the matrix plate as rigidly as possible at the time the filler is being pressed into the matrix, a supporting 90 roll 45 (Figure 3), loosely mounted on the shaft 25, engages the under side of the matrix plate.

Referring again to Figure 4, with occasional reference to Figures 5 and 6, the 95 magazine in which the fillers are stacked and the mechanism for feeding them one by one to the matrix plate will be described. The magazine has three forward upright guides 47, 46 and 48 for engaging the rounded toe portions of the fillers. The upright 48 has been omitted from Figure 4 but is shown in Figure 2. At the rear end of each filler is a groove 300 and into these grooves extends a fourth guide. This guide consists of 100 two stationary, spaced plates 49 and located between them a vibrator 51. The purpose of this vibrator is to ensure that, as the lowermost fillers of the stack are successively fed from the magazine, the stack shall settle. 105 The vibrator 51 is fastened at its upper end by a set screw 52 to a rock-shaft 53 having fast at one end an arm 55 to the lower end of which is pivoted a link 57, the end of the link which is remote from the arm 55 being 110 pivotally fastened to the knife 43 (Fig. 2). This knife, as will presently be explained, is oscillated in an orbital path, which lies in the plane of the cut, and consequently the link 57 is reciprocated, the shaft 53 rocked, 115 and the vibrator 51 actuated. The stationary upright plates 49, which lie at each side of the vibrator 51, are rigid with a block 59, said block also having rigid with it a yoke 61 in which the rock-shaft 53 has its bearings. The block 59 is supported above a feed slide 61 upon the upper ends of stationary rods 63 which pass through slots formed in the feed slide. 120

The feed slide 61 has in its forward edge 130

a recess provided with a projection 64 shaped to enter the groove 300 which is formed in the rear end of each filler. This feed slide is slidable upon the guides 19 over the 5 matrix plate and is urged forward at all times by tension springs 65 which are connected at their rear ends to the feed slide 61 and at their forward ends to screws 67 (Fig. 2) carried by the frame of the machine. 10 The feed slide 61, which is shown in Figures 2 and 4 in its forward position just after having delivered a filler to the matrix, is moved to this position by the springs 65, the limit of said movement at this time being determined by contact of a set screw 69 with the rear edge of the plate 9, said set screw being threaded through the down-turned outer end of a tail-piece 71 which is fastened at its inner end by screws 73 15 to the feed slide 61. The feed slide is picked up by the reciprocating plate 9 during the rearward movement of said plate, moved to the rear against the force of the springs 65, and then released at the proper time to permit the springs to move the feed slide forward so as to push the lowermost filler of the stack into the matrix. To this end (see Figures 4 and 5) there are fastened to the feed slide 61 two leaf springs 75 the forward free ends of which extend down through slots 77 in the feed slide. Carried by the plate 9 are two buttons, one of which is shown at 79 in Figure 5, the lower, rounded ends of the buttons extending below the 20 plate 9 so that, when the plate 9 is moved far enough to the rear, the lower ends of these buttons will contact with stationary inclines, one of which is shown at 81 in Figure 5. The heads of the buttons 79 are normally located below the upper surface of the plate 9; and above said heads are recesses in the plate 9, one of said recesses being shown at 83 in Figure 5. Assuming now that the feed slide 61 is in its forward position, as shown in Figure 4, and has just delivered a filler to the matrix plate, that plate moves forward to carry the filler past the skiving mechanism, the feed slide at first moving with the matrix plate until further forward movement of the feed slide is arrested by contact of the rear ends of slots 25 85 in said slide with the stems of cap-screws 87 which serve, with the rods 63, as guides for the feed slide. After the filler has been skived, it is removed from the machine by mechanism presently to be described. At this time the free ends of the stiff leaf springs 75 are pressing down upon the upper surface of the plate 9. As said 30 plate 9 moves back to its rearward position to receive another filler, the free ends of the leaf springs 75 snap into the recesses 83 (Fig. 5) and the feed slide 61 is thereby picked up by the rearwardly moving plate 9 and moved 35 rearwardly until the rounded lower ends of the buttons 79 ride up on the stationary inclines 81. The buttons then push the free ends of the leaf springs 75 out of the recesses 83, and the springs 65 pull the feed slide 61 quickly forward to feed another 40 filler into the matrix. The feed slide 61 is thus connected temporarily with the plate 9 during a portion of the rearward movement of said plate and then, at the proper time, this connection is broken and the feed slide moves forward with respect to the plate. It will be noted that the feed slide 61 not only acts to deliver a filler to the matrix but serves, during the skiving of that filler, to support the stack of blanks in the magazine; and that the stack of blanks; as it diminishes is supported alternately by the feed slide and by the plate 9. 45

In order to facilitate the cutting operation, the knife is moved continuously in a manner to produce a draw cut, the movement in the illustrated machine, as has been stated, being in an orbital path in the plane of the cut. To this end the knife 43, as best shown in Figs. 3 and 8, has extensions at its opposite ends having bushings 88 to receive crank pins 89 held at the enlarged upper ends of upright shafts 91. The bushings 88 are rigidly fastened to the knife 43 by nuts 95 threaded on the bushings; and the bushings are prevented from rising by nuts 97 threaded upon the upper ends of the crank pins 89 and by washers between the nuts and the bushings. The crank pins 89 have T-shaped bases which are adjustable in T-shaped grooves in the heads of the shafts 91, screws 90 being provided for adjusting the crank pins so as to change their throw when desired, said screws serving also to hold the crank pins in adjusted position. The upright shafts 91 have at their lower ends bevel gears 99 which mesh with bevel gears 101 fast to a horizontal shaft 103, said shaft being driven continuously from any suitable source of power through a pulley 105. The knife thus moves in an orbital path the plane of which is horizontal and produces a series of draw cuts upon the work, the upright shafts 91 being rotated at high 50 55 60 65 70 75 80 85 90 95 100 105 110 115 120 125 speed.

In operating upon work such as has been described which comprises absorbent material impregnated with a thermoplastic substance, considerable difficulty is encountered in making a clean smooth cut. It has been found that the character of the cut is greatly improved by actuating the knife to produce a draw cut, and that it can be further improved by heating the knife. Accordingly, an electric heating unit 107 (Fig. 3) is mounted in a thin-walled hollow holder 109 which is fastened to the frame of the machine and extends over and close to a

portion of the knife, said unit being supplied with electricity from any suitable source of electric current.

As the matrix plate carrying a filler is presented to and fed past the knife, the filler is pressed down into the matrix, as has been stated, by a presser roll 41. Inasmuch as the filler at this time must be distorted in such manner that only the desired portion 10 of it lies in the path of the knife, this roll should have provision for yielding properly. The illustrated roll 41 is a rubber one, that is, it comprises an iron core and a body portion of vulcanized rubber. This presser roll 15 41 is oscillated from the segmental rack 29 in the following manner:—The roll 41 is fastened to the middle of a shaft 111 at one end of which a gear 113 (Fig. 1) is fastened, said gear meshing with an idle gear 115. The last-named gear meshes with a second idle gear 117 which in turn meshes with the pinion 27, said pinion being oscillated, as has been explained, by the segmental rack. With this construction the presser roll 25 is rotated in a direction to aid the matrix plate in advancing the work when said plate is moving forward. The construction is such that the peripheral speed of the roll is equal to the rate of bodily movement of the reciprocating matrix plate.

As has been stated, the shaft 37 (Fig. 1), from which the matrix plate and the presser roll are driven, is rotated by a belt 39 through a one-revolution clutch. Inasmuch as any suitable one-revolution clutch may be used and the details of construction of the one which is partially illustrated form no part of the present invention, no description of it will be given other than to state that 40 the clutch shown is of the well-known Horton type and that, by manipulating the rod 119 by means of a treadle (not shown) in such manner as first to push the rod up and then to release it, the shaft 37 is caused to 45 make one revolution and come to rest.

The matrix plate in its forward movement carries the filler past the skiving mechanism into position to be engaged by a picker mechanism (Figs. 1 and 2) which lifts the filler off from the matrix plate just as the plate reverses its direction of movement and then, when the plate has been retracted, drops the filler between the guides 19 to the floor or into a suitable receptacle. A picker 121 50 (Fig. 1) is formed at the lower end of a small rod 123 which has formed upon it two spaced collars 125, 127. The collar 125 is slidable in a socket having an open lower end and located in the enlarged outer end 55 of the horizontal arm 129 of a bell-crank lever pivoted at 131 to the frame of the machine and having a vertical arm 239 provided with a fork at its upper end to embrace an eccentric 33 on a one revolution 60 shaft 135 mounted in bearings in the frame 65

of the machine. At the upper end of the enlarged outer end of the arm 129 is a small bore through which the picker rod 123 passes freely. A nut 124, threaded on the rod, provides means for adjusting the rod vertically; 70 and a coiled spring 126 rests at its lower end upon the collar 125 so that the downward movement of the arm 129 is imparted to the picker rod through this spring. The shaft 135 comes to rest in the position shown in 75 Fig. 1 with the picker 121 in raised position. When one revolution is imparted to the shaft, the picker is first forced down to cause it to penetrate a filler on the matrix plate and is then raised to lift the filler from the plate. Mounted loosely on the shaft 135 80 is a pulley 137 which is driven continuously by a belt (not shown) from any suitable source of power; and, adapted to connect the pulley with the shaft, is a one-revolution 85 clutch. Since any suitable one-revolution clutch may be used and the details of the one illustrated form no part of the present invention, said clutch will not be described other than to state that the illustrated clutch 90 is of the well-known Horton type and that, when the arm 139 (Fig. 1) is pushed up and then allowed to drop back, the shaft 135 will make one revolution and come to rest. This arm 139 is pivoted at 141 to one end of an 95 arm 143 the hub of which is fast to the outer end of a short shaft 145 rotatably mounted in the frame of the machine; and fast to the inner end of this short shaft is a finger 147 which extends up into the path of reciprocation of the matrix plate. When, 100 therefore, the matrix plate approaches the end of its forward movement, it strikes this finger 147 and trips the clutch with the result that the picker 121 penetrates the skived filler and lifts it from the matrix plate. The picker holds the filler suspended until, upon the rearward movement of the matrix plate, an abutment 149 (Fig. 1) fast to the under side of the plate strikes the upper end of a lever 151, which is pivoted to the frame of the machine at 153 and actuates mechanism for stripping the filler from the picker point and permitting it to fall between the guides 19 to the floor or into a receptacle placed 105 to receive it.

This stripping mechanism comprises a stripper in the form of a sleeve 155 having extending into it from its lower end to near its top a comparatively large bore to receive slidably the collar 127 on the picker rod 123 and a coiled spring 157. The top of the member 155 has a smaller bore through which passes the rod 123, the spring 157 resting upon the collar 127 and serving to 110 hold the stripper member normally in the inoperative position shown. In order to push this stripper member down at the proper time and thus strip from the picker 121 a filler which it is holding, an arm 159, 115

the hub of which is loosely mounted on the shaft 135, is pulled down, said arm having at its outer end a yoke between the arms of which is pivotally mounted, on conically pointed screws 161, a ring 163. The arm 159 is connected by a link 165 with an arm 166 the hub of which is fast to a small rock-shaft 169. This rock-shaft extends through the machine from side to side thereof and 10 has fast to that end which is remote from the arm 166 a second arm 167 the outer end of which is connected by a long link 171 with the lower end of the lever 151. Consequently when the abutment 149 on the matrix 15 plate strikes the upper end of the lever 151 and swings it in a clockwise direction, the stripper 155 is moved down on the rod 123 to strip from the picker 121 the skived filler which it is then holding; and when the 20 abutment 149 moves away from the lever 151, the stripper returns to the position shown under the influence of the spring 157 in the stripper.

The operation of the machine is as follows:—A stack of fillers is placed in the magazine and power is applied to the pulleys 105, 40 and 137. The pulleys 40 and 137 run idly on their respective shafts 37 and 135 but the pulley 105 rotates its shaft 30 103 and causes the knife 43 to move rapidly in an orbital path. Electric current is supplied to the heating unit to heat the knife. The vibrator 51 of the magazine, owing to its connection with the moving knife, is actuated to cause the fillers to settle down in the magazine. As soon as the knife has become 35 properly hot, the clutch which is adapted to connect the pulley 40 with the shaft 37 is thrown in to impart one revolution to 40 the shaft 37 and consequently one complete reciprocation to the matrix plate. At this moment the matrix plate is near the rear end of its path, and the free ends of the leaf springs 75 of the feed slide 61 are in the 45 recesses 83 in the matrix plate. The matrix plate first finishes its rearward movement, just before the end of which the buttons 79 ride up on the inclines 81 and release the feed slide which thereupon moves forward 50 under the influence of the springs 65 so as to deliver the lowermost filler of the stack into the matrix of the matrix plate. The matrix plate moves forward carrying the filler past the skiving mechanism, which cuts 55 the recess 200. As the forward end of the matrix plate strikes the finger 147, the one-revolution clutch controlled by it imparts one revolution to the shaft 135 with the result that the picker 121 penetrates the skived 60 filler and lifts it off from the matrix plate. The matrix plate on its rearward movement picks up the feed slide by means of the leaf springs 75, moves it part way back, and comes to rest. In doing so, the abutment 65 149 on the matrix plate encounters the lever

151 and swings it about its pivot whereupon the stripper 155 moves down to push the skived filler from off the picker 121. As thus described, the one-revolution clutch which controls the rotation of the shaft 37 70 must be thrown in once for every filler which is skived. If desired, however, the trip lever 175 (Fig. 1) may be swung to the left and fastened in inoperative position, in which case the shaft 37 will rotate continuously as long as power is applied to the pulley 40 through the belt 39, and the fillers in the magazine will be delivered one by one 75 to the matrix plate and operated upon.

Although the invention has been set forth 80 as embodied in a particular machine designed to operate upon a particular kind of work, it should be understood that the invention is not limited in the scope of its application to any particular kind of work nor to 85 the particular machine which has been shown and described.

The filler disclosed herein forms no part of the invention and is shown, described and claimed in application Serial No. 252,868, 90 filed Sept. 6, 1918, in the name of this inventor, upon which United States Letters Patent No. 1,582,260 were granted April 27, 1926.

Having thus described the invention, what is claimed as new and desired to be secured 95 by Letters Patent of the United States is:—

1. A machine of the class described having, in combination, a knife, means for moving the knife in a path to cause it to produce a draw cut, a plate having a matrix to receive a blank, means for pressing the blank into the matrix, and means for causing relative movement of approach between the knife and the matrix plate. 100

2. A machine of the class described having, in combination, a knife, means for moving the knife in an orbital path in the plane of its cut to cause it to produce a draw cut, a plate having a matrix to receive a blank, means for pressing the blank into the matrix, and means for causing relative movement of approach between the knife and the matrix plate. 110

3. A machine of the class described having, in combination, a knife, means for moving the knife in a path to cause it to produce a draw cut, a plate having a matrix, means for pressing a blank into the matrix, and means for moving the plate with the blank upon it into operative relation to the knife 115 and pressing means.

4. A machine of the class described having, in combination, a knife, means for moving the knife in an orbital path in the plane of its cut to cause it to produce a draw cut, a plate having a matrix, means for pressing a blank into the matrix, and means for moving the plate with the blank upon it into operative relation to the knife and pressing means. 125

5. A machine of the class described hav- 130

ing, in combination, a knife, a magazine for a stack of blanks, a matrix plate, means for delivering a blank from the stack to the matrix of the plate, and means for reciprocating the plate to cause it to feed the blank to the knife and to return into position to receive in its matrix another blank from the stack.

6. A machine of the class described having, in combination, a knife, means for moving the knife in a path to produce a draw cut, a matrix plate, and means for reciprocating the plate to cause it to feed a blank to the knife and to return into position to receive in its matrix another blank.

7. A machine of the class described having, in combination, a knife, means for moving said knife in a path to cause the knife to produce a draw cut, a plate having a matrix to receive a blank, a roll having a yielding periphery located adjacent to the knife for pressing the blank into the matrix, and means for producing relative movement of approach between the knife and roll and the matrix plate.

8. A machine of the class described having, in combination, a knife, means for moving said knife in an orbital path to cause the knife to produce a draw cut, a plate having a matrix to receive a blank, a roll having a yielding periphery located adjacent to the knife for pressing the blank into the matrix, and means for producing relative movement of approach between the knife and roll and the matrix plate.

9. A machine of the class described having, in combination, a knife, means for moving said knife in a path to cause the knife to produce a draw cut, a plate having a matrix to receive a blank, a rubber roll located adjacent to the knife for pressing the blank into the matrix, and means for producing relative movement of approach between the knife and roll and the matrix plate.

45 10. A machine of the class described having, in combination, a magazine for a stack of blanks, a matrix plate, means for delivering a blank from the stack to the matrix of the plate, a roll having a yielding periphery for pressing the blank into the matrix, a knife located adjacent to the roll, and means for reciprocating the matrix plate to cause it to feed the blank to the roll and knife and to return into position to receive another blank from the stack.

11. A machine of the class described having, in combination, a magazine for a stack of blanks, a matrix plate, means for delivering a blank from the stack to the matrix of the plate, a rubber roll for pressing the blank into the matrix, a knife located adjacent to the roll, and means for reciprocating the matrix plate to cause it to feed the blank to the roll and knife and to return

into position to receive another blank from the stack.

12. A machine of the class described having, in combination, a knife, means for moving the knife in a path to produce a draw cut, a plate having a matrix to receive a blank, means for pressing the blank into the matrix, and means for producing relative movement of approach between the knife and the matrix plate.

13. A machine of the class described having, in combination, a knife, means for moving the knife in an orbital path in the plane of its cut, means for heating the knife, a plate having a matrix to receive a blank, means for pressing the blank into the matrix, and means for producing relative movement of approach between the knife and the matrix plate.

14. A machine of the class described having, in combination, a knife, a magazine for a stack of blanks, a plate located at a level below that of the lowermost blank of the stack, a feed slide located at the level of the lowermost blank, and means for reciprocating the plate and the feed slide to advance to the knife one at a time the successively lowermost blanks of the stack in such manner that during the operation of the knife upon a blank, the stack is supported by the feed slide.

15. A machine of the class described having, in combination, a magazine for a stack of blanks, skiving mechanism, a matrix plate reciprocable in a path below the lowermost blank of the stack, a feed slide reciprocable in the plane of the lowermost blank, means for causing the feed slide to deliver the forward end of the lowermost blank into the forward portion of the matrix, means for thereafter moving the feed slide and the matrix plate in unison to advance the blank, and means for arresting the movement of the feed slide in position to support the stack of blanks in the magazine.

16. A machine of the class described having, in combination, skiving mechanism, a plate, means for reciprocating the plate from blank-receiving position to and past the skiving mechanism so that successive blanks received by the plate will be skived, means for lifting each blank from the plate after it has been skived, and means for disengaging each skived blank from the lifting means.

17. A machine of the class described having, in combination, skiving mechanism, a plate, means for reciprocating the plate from blank-receiving position to and past the skiving mechanism so that successive blanks received by the plate will be skived, means for lifting each blank from the plate after it has been skived, and means operated by the plate during its movement to blank-

receiving position for disengaging the blank from the lifting means.

18. A machine of the class described having, in combination, a magazine for a stack 5 of blanks, skiving mechanism, a plate for feeding the blanks one by one to and past the skiving mechanism, means for lifting the skived blank from the plate, and means for disengaging the blank from the lifting 10 means.

19. A machine of the class described having, in combination, a magazine for a stack 15 of blanks, skiving mechanism, a plate for feeding the blanks one by one to and past the skiving mechanism, means for lifting the skived blank from the plate, and means operated by the plate during its movement toward the magazine for disengaging the blank from the lifting means.

20. A machine of the class described having, in combination, a knife, a magazine for a stack of blanks, a matrix plate located at a level below that of the lowermost blank 25 of the stack, a feed slide located at the level of the lowermost blank, yielding means for moving the feed slide to deliver the lowermost blank to the matrix plate, means for moving the plate alternately toward the knife and toward the magazine, and means 30 for causing the plate in its movement toward the magazine, first to move the feed slide in opposition to the yielding means and then to release the feed slide.

21. A machine for skiving a recess in a blank made of felted material impregnated 35 with a thermoplastic substance having, in combination, a knife, means for operating the knife in a manner to cause it to make a draw cut, means for heating the knife, a feed member having a matrix, and means 40 for pressing the blank into the matrix and for operating the feed member to present the blank to the knife.

22. A machine of the class described having, in combination, a skiving knife, means 45 including a member having a matrix therein for distorting a blank and advancing it to the knife, means for moving the knife in a path to produce a draw cut, and means 50 for heating the knife.

23. A machine of the class described having, in combination, skiving mechanism, a plate, means for reciprocating the plate from blank-receiving position to and past 55 the skiving mechanism so that successive blanks received upon the plate will be skived, a picker for lifting each blank from the plate after the blank has been skived, and means for stripping the blank from the 60 picker.

In testimony whereof I have signed my name to this specification.

SAMUEL R. CUTLER,
*Administrator of the Estate of Frederick
M. Furber, Deceased.*
